UNITED STATES PATENT OFFICE

172,558

BROOCH OR THE LIKE

Alfred Philippe, Scarsdale, N. Y., assignor to Tri-fari, Krussman & Fischel, Inc., New York, N. Y.

Application February 17, 1954, Serial No. 29,080

Term of patent 7 years

(Cl. D45—19)

To all whom it may concern:

Be it known that I, Alfred Phillippe, a citizen of the United States of America, residing in Scarsdale, county of Westchester, and State of New York, have invented a new, original, and ornamental Design for a Brooch or the like, of which the following is a specification, reference being had to the accompanying drawing, forming part thereof.

Fig. 1 is a plan view of a brooch or the like, showing my new design.

Fig. 2 is an edge view thereof.

I claim:

The ornamental design for a brooch or the like, substantially as shown.

No references cited.
